US0D1096559S

(12) **United States Design Patent** (10) **Patent No.:** **US D1,096,559 S**
(45) **Date of Patent:** **** Oct. 7, 2025**

(54) **FRONT PORTION FOR A MOTOR VEHICLE**

(71) Applicant: **TOYOTA JIDOSHA KABUSHIKI KAISHA**, Toyota (JP)

(72) Inventors: **Tomonori Matsumoto**, Irvine, CA (US); **Joonsung Ea**, Canton, MI (US)

(73) Assignee: **TOYOTA JIDOSHA KABUSHIKI KAISHA**, Toyota (JP)

(**) Term: **15 Years**

(21) Appl. No.: **29/922,778**

(22) Filed: **Dec. 26, 2023**

(57) **CLAIM**

The ornamental design for a front portion for a motor vehicle, as shown and described.

DESCRIPTION

FIG. 1 is a front left perspective view of a front portion for a motor vehicle showing our new design;

FIG. 2 is a rear right perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The de-emphasized and halftone portions shown in the figures illustrate environmental structure of the front portion for a motor vehicle that forms no part of the claimed design. The bottom view of the front portion for a motor vehicle forms no part of the claimed design.

1 Claim, 7 Drawing Sheets
